UNITED STATES PATENT OFFICE

2,373,958

THREADING DEVICE

Morton Hornstein, New York, N. Y., assignor to
 Breslee Mfg. Company, New York, N. Y., a co-
 partnership composed of Israel E. Levy and
 Arthur A. Gardner

Application June 7, 1944, Serial No. 539,225

4 Claims. (Cl. 242—52)

This invention relates to threading devices.

One object of the invention is the provision of means to facilitate the winding of a threading device, i. e., a thread carrier and guide of the netting-needle type.

Another object of the invention is to provide an improved method of providing a threading device of the character described with a winding of thread, cord or the like.

A further object of the invention is the provision of means for holding a normally flat threading device in longitudinally-flexed bowed condition in order to facilitate the winding thereon of a coil of thread, cord or the like.

The invention as well as the above mentioned and other objects thereof will be more fully understood from the following description, reference being had to the accompanying illustrative drawings.

In the drawings:

Fig. 1 is a view in elevation of winding apparatus embodying the present invention;

Fig. 2 is a view in elevation as seen from the left of Fig. 1;

Fig. 3 is a side view of a threading device;

Fig. 4 is a longitudinal sectional view on the line 4—4 of Fig. 3;

Figs. 5 and 6 are transverse sectional views on the lines 5—5 and 6—6, respectively, of Fig. 3;

Fig. 7 is a front view of the holder for the threading device;

Fig. 8 is a view similar to Fig. 7 showing the threading device mounted in the holder;

Fig. 9 is a side view in elevation of the holder with the threading device mounted therein;

Fig. 10 is a longitudinal sectional view of the holder on the line 10—10 of Fig. 7;

Fig. 11 is a longitudinal sectional view on the line 11—11 of Fig. 8;

Fig. 12 is a sectional view on the line 12—12 of Fig. 7.

Referring now to the drawings in detail, there is shown in Figs. 3 to 6 a threading member 10 which is of the netting-needle type, said threading member being adapted to have wound thereon an elongated coil of thread or cord as indicated at 12 in Fig. 2, said coil being wound in the form of elongated convolutions extending around one of the furcations 14 of the bifurcated end portion 15 and around the pin 16 whereby the coil extends longitudinally of the threading member in a known way. The threading member 10 is normally flat and is formed of a plastic or other suitable stiff but flexible material and is provided with an open-

ing 18 within which the pin 16 is positioned. Pin 16 is rigid and is preferably formed of metal, said pin, having a bifurcated end portion 20 which is secured to the adjacent end portion of the intermediate part 22 of the threading member in any suitable way as by rivets 24. One end 26 of the threading member is pointed in order to facilitate the projection of the threading member through a loop. It will be understood that the threading member 10 is of a size to be conveniently held in the hand for manipulating the threading member for applying the cord or thread of the coil carried thereby for the desired purpose.

In accordance with the present invention, provision is made for holding the threading member 10 in position to facilitate the winding of the coil or thread thereon. The holder 28 provided for this purpose is illustrated in Figs. 1, 2 and 7 to 11. Said holder is rigid and may be formed of wood or of any other suitable material and has a longitudinally curved surface 30 at one side thereof and a flat surface 32 at its opposite side. At the curved side thereof said holder is provided with a recess 34 to receive one of the end portions or furcations 14 of the threading device as shown in dotted lines in Fig. 8 and in full lines in Fig. 11, and with a recess 36 terminating in an undercut closed end 37 to receive the pointed end portion 26 of said threading member as illustrated in Figs. 8 and 11. A metal band 38 extends transversely around the holder 28 in position to overlie the end of recess 34 and the end portion 14 of the threading member 10 which is positioned in said recess and as clearly illustrated in Figs. 8 and 11. When the threading member 10 is positioned in the holder 28, said threading member is flexed or bowed longitudinally thereof, conforming generally in longitudinal curvature to the curved surface 30 of holder 28, while the pin 16 and one of the end portions 14 are disposed in spaced relation to the surface 30 of holder 28, as illustrated in Figs. 1 and 9. The parts of the holder 28 at the closed ends of recesses 34 and 36 constitute means to engage the opposite ends, respectively, of threading member 10 and to hold the latter in longitudinally-flexed bowed condition, as illustrated in Fig. 11 (see also Fig. 9), the space between said member-engaging means being less than the length of said member. Holder 28 has a part 39 disposed laterally of recess 34 which engages a part of member 10 inwardly of its bifurcated end portion 15 for holding one of the furcations 14, namely the

furcation which is not disposed in recess 34, in spaced confronting relation to the curved surface of the holder. An integral rib 41 is positioned in recess 26, centrally, to form a bearing for the pin 16 of threading member 10 to form a firm support for said pin when the threading member is positioned in the holder. As illustrated in Figs. 9 and 11, when the threading member 10 is mounted in the holder 28, the pin 16 and one of the furcations 14 are displaced from the general line of curvature of the bowed threading member, thus providing room for the looped ends of the convolutions of the winding formed on said threading member. It will be understood that when the threading member 10 is thus held in holder 28 a length of cord, thread or the like, can be easily wound on the threading member, with the convolutions extending longitudinally of said threading member as illustrated in Fig. 2, the opposite ends of said convolutions engaging the pin at the side thereof adjacent the opening 18 and the forked end of the threading member near the end portion or furcation 14 which is spaced outwardly from the curved surface 30 of the holder 28 in confronting relation to said surface.

In accordance with the present invention, it is preferred to rotate the holder 28 with the threading member 10 mounted therein for winding the cord on said threading member. For this purpose, holder 28 is mounted on a rotary shaft 40 of the winding apparatus 42 illustrated in Figs. 1 and 2. More particularly, holder 28 is provided with a shaft-receiving opening 44 and with a nut-receiving recess 46. As illustrated in Fig. 1, the holder is mounted on the threaded end 48 of shaft 40 and is secured to said shaft for rotation thereby in any suitable way, the securing means being here shown as a nut 49 which is positioned in the nut-receiving recess 46 and by a nut 50 which engages the flat surface 32 of holder 28. Shaft 40 is journaled for rotation in a bearing 52 carried by a frame member 54. The means for rotating shaft 40 whereby to rotate holder 28 comprises as here shown a pulley 56 mounted on said shaft and connected to a driving pulley 58 by means of a belt 60. As here shown pulley 58 is operated by a hand crank 62, but said pulley can be power operated if desired. It will be observed that holder 28 is mounted for rotation about an axis substantially normal to the cord of the arc of longitudinal curvature of the threading member 10 in the bowed condition thereof whereby said threading member is rotated in its own plane for the winding of the cord or thread thereon. The cord or thread C to be wound on the thread carrier 10 is supplied to the latter from a spool S which as illustrated in Figs. 1 and 2 is mounted for rotation in bearing arms 64 fixed to the base 66 of the frame of the apparatus. From the spool S the cord C extends through a guide opening 68 in the arm 70 of a bracket 72 which as here shown is secured to the bearing member 52. A cord tensioning device 74 is mounted on the arm 70 of bracket 72 by means of an attaching bracket 76 which is secured to arm 70 of bracket 72. Said tensioning device comprises a disk 78 mounted on a pin 80 and a companion disk 82 which is movable longitudinally of pin 80 and which is spring pressed toward disk 78 by a spring 84, the pressure of which is adjustable by a nut 86 threaded on the outer end of pin 80. The cord C, in passing from the supply spool S to the threading member 10 in the hold-

er 28, is frictionally engaged by disks 78 and 82 whereby to tension the cord between said tensioning device 74 and the threading member 10 while the latter is rotated for forming the winding thereon. If desired, a brake of any well known type may be applied to the spool S to tension the cord between said spool and the tension device 74.

It will be understood that in utilizing the apparatus of the present invention for forming a winding on the threading member 10, the latter is placed in the holder 28 as described above and that after one or two convolutions of the cord are wound on the threading member by hand, the shaft 40 is rotated thereby to rotate the holder 28 and the threading member 10 carried thereby for completing the winding operation, the cord being drawn from the spool S by the tension imparted to the cord as a result of the rotation of the threading member 10 in the rotating holder 28. When the desired length of cord is wound on the threading member 10, the latter is removed from the holder 28 by disengaging the end 14 from the recess 34 and the end 26 from the recess 36.

While I have shown and described the presently preferred mode of practicing my invention and the presently preferred apparatus embodying the same, it will be understood that various changes may be made without departing from the underlying idea of the invention within the scope of the appended claims.

Having thus described my invention, what I claim and desire to secure by Letters Patent is:

1. Means for use in forming a winding on a normally flat flexible threading member of the netting-needle type which is provided with a bifurcated end portion and an opening in which a longitudinally extending pin carried by said member is positioned, said means comprising a holder having a longitudinally curved surface provided with recessed portions spaced from each other longitudinally of the holder and positioned to engage and releasably hold the opposite ends of said threading member against movement longitudinally of the holder whereby to hold the threading member in longitudinally-flexed bowed condition, but with said pin and one of the furcations of said bifurcated end portion displaced from the general line of curvature of the bowed member at the convex surface thereof.

2. Means for use in forming a winding on a normally flat flexible threading member of the netting-needle type which is provided with a bifurcated end portion and an opening in which a longitudinally extending pin carried by said member is positioned, said means comprising a holder having a longitudinally curved surface provided with recessed portions spaced from each other longitudinally of the holder and positioned to engage and releasably hold the opposite ends of said threading member against movement longitudinally of the holder whereby to hold the threading member in longitudinally-flexed bowed condition, but with said pin and one of the furcations of said bifurcated end portion displaced from the general line of curvature of the bowed member at the convex surface thereof, and means mounting said holder for rotation in a plane substantially parallel to the plane of said member whereby to rotate the latter in its own plane.

3. Means for use in forming a winding on a normally flat flexible threading member of the

netting-needle type which is provided with a bifurcated end portion and an opening in which a longitudinally extending pin carried by said member is positioned, said means comprising a holder having means positioned to support said member and to hold the latter releasably in longitudinally-flexed bowed condition but with said pin and one of the furcations of said bifurcated end portion displaced from the general line of curvature of the bowed member at the convex surface thereof, said holder having parts for positioning said pin and said one of the furcations in spaced confronting relation to the adjacent parts of said surface of the holder.

4. Means for use in forming a winding on a normally flat flexible threading member of the netting-needle type which is provided with a bifurcated end portion and an opening in which

5 a longitudinally extending pin carried by said member is positioned, said means comprising a holder having means positioned to support said member and to hold the latter releasably in longitudinally-flexed bowed condition but with said pin and one of the furcations of said bifurcated end portion displaced from the general line of curvature of the bowed member at the convex surface thereof, said holder having parts 10 for positioning said pin and said one of the furcations in spaced confronting relation to the adjacent parts of said surface of the holder, and means mounting said holder for rotation in a plane substantially parallel to the plane of said member whereby to rotate the latter in its own plane.

MORTON HORNSTEIN.
